Inventor

J. P. Nielsen.

By *A. Knutson Jr.* Attorney

UNITED STATES PATENT OFFICE.

JENS P. NIELSEN, OF NEW YORK, N. Y.

ELECTRIC-LAMP-SOCKET WAFER FUSE.

Application filed September 22, 1923. Serial No. 264,180.

REISSUED

To all whom it may concern:

Be it known that I, JENS P. NIELSEN, a subject of the King of Denmark, residing at New York city, in the county of New York and State of New York, have invented certain new and useful Improvements in Electric-Lamp-Socket Wafer Fuses; and I do hereby declare the following to be a full, clear, and exact description of the invention, such as will enable others skilled in the art to which it appertains to make and use the same.

The present invention has for its object to prevent the surreptitious and unauthorized use of electric currents by persons occupying rooms or other quarters which are electrically lighted. It is a common practice to remove the electric lamp and plug in a heater, curling iron and other appliance consuming current, thereby adding materially to the running expense of a hotel, rooming house and the like.

The present invention provides a fuse in the form of a wafer which may be introduced into the ordinary lamp socket and which will blow when any appliance requiring a heavy current consumption is plugged into the socket after the lamp has been removed, said fuse being concealed within the socket and not readily renewable by the uninitiated.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a plan view of a wafer fuse embodying the invention,

Figure 2 is an edge view thereof,

Figure 3 is a sectional view of the fuse showing it applied to a lamp socket,

Figure 4 is a sectional view on the line 4-4 of Figure 1, and

Figure 5 is a detail view of a key for rotating the fuse when placing it in position or removing it from the socket.

Corresponding and like parts are referred to in the following description and

designated in the several views of the drawings by like reference characters.

The fuse is of flattened form suggestive of a wafer and is constructed of insulating material such as fiber, rubber or composition, and for convenience comprises similar or like sections 1 and 2 between which is formed a central space 3 which contains a fuse wire 4 approximating one ampere capacity and which will blow when a current is passing of greater capacity than required for an electric lamp. The inner or opposing faces of the sections 1 and 2 are recessed to form the space 3. The outer edge of the fuse is formed with screw threads 5 to match the screw threads of an ordinary lamp socket 6. Openings 7 are provided in a side of the fuse to receive the nib of a key 8 which is required to rotate the fuse when placing the same in position or removing it from the socket. Centrally disposed contacts 9 are provided at opposite sides of the fuse and may be held in place by any suitable means such as screws 10, the latter also serving as means for securing the ends of the fuse wire 4. The two sections 1 and 2 may be held when assembled by any suitable means, such as screws 11, the latter admitting of replacing the fuse wire 4 when blown, so that the fuse may be repeatedly used.

To prevent arcing between the contacts after the fuse blows, any fuse filler may occupy the space 3, or a sheet of mica 12 may be clamped between the sections 1 and 2 and have an opening for the passage of the fuse wire 4. The opening in the mica 12 is out of line with the contacts to prevent the formation of a direct passage for the current.

What is claimed is:

1. In combination with an electric lamp socket, a fuse disposed in the socket and consisting of two wafers having matching recesses therein together forming a central space, a fuse element bridging said space, terminals on the wafers and connected with said fuse elements, and the margin of said wafers formed with screw threads to engage the screw threads of the socket.

2. In combination with an electric lamp socket, a fuse disposed in the socket and occupying a minimum amount of the space thereof, said fuse being of a capacity to blow upon attempted consumption of cur-

rent heavier than that required for the lamp normally occupying the socket, the fuse having wafers provided with marginal screw threads to engage the screw threads of the socket, the fuse having an internal space, a diaphragm of insulation bridging said space, a fuse element carried by the fuse, and said element passing through the diaphragm in disalignment with its terminals for the purpose specified.

3. In combination with an electric lamp socket, a fuse disposed in the socket and occupying a minimum amount of the space thereof, said fuse being of a capacity to blow upon attempted consumption of cur-

rent heavier than that required for the lamp normally occupying the socket, the fuse consisting of disks having their inner surfaces cut away to provide a space, a diaphragm of insulation bridging said space, means securing the disks together and said diaphragm between them, terminals on the disks, a fuse element extending from one terminal to the other terminal, and said element passing through the diaphragm in disalignment with the axis of its terminals.

In testimony whereof I affix my signature.

JENS P. NIELSEN.
